J. H. CORE,
SPEED MEASURING AND CONTROLLING DEVICE,
APPLICATION FILED OCT. 10, 1917.

1,293,717.

Patented Feb. 11, 1919.

UNITED STATES PATENT OFFICE.

JAMES HENRY CORE, OF NASHVILLE, TENNESSEE.

SPED MEASURING AND CONTROLLING DEVICE.

1,293,717.

Specification of Letters Patent. Patented Feb. 11, 1919.

Application filed October 10, 1917. Serial No. 195,797.

To all whom it may concern:

Be it known that I, JAMES H. CORE, a citizen of the United States, and a resident of Nashville, in the county of Davidson and State of Tennessee, have invented a new and useful Improvement in Speed Measuring and Controlling Devices, of which the following is a specification.

My present invention relates generally to improvements in devices for measuring speed and controlling the speed of vehicles, and more particularly to improvements upon my Patent 1110960 of September 15, 1914, my aim being the provision of a more simple, generally effective construction and arrangement for the purposes which will hereinafter be set out in detail.

In the accompanying drawing, which illustrates my invention, and forms a part of this specification,

Figure 1 is a front elevation, the front plate being removed to better show the internal mechanism.

Fig. 2 is a detail horizontal section taken substantially on line 2—2 of Fig. 1, and

Fig. 3 is a front elevation with the casing complete.

Referring now to these figures, my invention which in its general nature resembles a speedometer and has, in fact, the ordinary functions thereof with certain additions I will now make plain, consists of a casing 10 vertically through which is mounted a shaft generally indicated at 11 and the lower end of which is provided with a gear wheel 12 for instance, as seen in Fig. 2, to be driven by an internally toothed gear 13, the latter of which is usually mounted at one end of a flexible shaft generally indicated at 14 and extending from the engine shaft of the vehicle in connection with which the device is used.

On the shaft 11 within the casing 10 is a centrifugal device in the nature of a governor, the weighted arms 15 of which are connected at their upper and lower ends, respectively, to collars 16 and 17, the former of which is stationarily secured to the shaft, and the latter of which is formed at the upper end of a sleeve 18 loosely disposed upon the shaft and provided with an annular groove in which is seated an actuating ring 19.

Coiled around the shaft 11 between the collars 16 and 17 is a spring 20, the function of which is to resist upward movement

of the collar 17 with its sleeve 18 and thus resist outward movements of the governor arms 15 in opposing their tendency to so move under the centrifugal force of rotation of the shaft 11.

Above the upper end of the shaft 11, and loosely mounted upon a shaft 21, is a horizontal number wheel 22, the axis of which is in the same plane with the axis of the shaft 11, said shaft 21 having a gear 23 secured thereto below the number wheel 22 engaged by a horizontal rack 24, the latter of which is shiftable in guides 25 and controlled by a spring 24a.

One end of the rack 24 is engaged by the upright arm of a bell crank lever 26, the lower horizontal arm of which is pivotally connected to the upper end of a connecting rod 27, the lower end of which is similarly connected to the outer end of a lever 28 fulcrumed intermediate its ends at 29 within the casing and having a laterally projecting pin 30 at its inner end extending through the slot of an extension 19a at one side of the actuating ring 19.

Thus, when under the centrifugal force, the collar 17 rises against the tension of spring 20 with its sleeve 18 and the actuating ring 19, lever 28 is rocked upon its fulcrum 29 and the bell crank lever 26 is rocked upon its fulcrum through the connecting rod 27. This operates to shift the rack bar 24 in the direction of its length and, through its connection with gear 23, causes rotation of the number wheel 22. The numbered face of the wheel 22 shows, in use, through a sight opening 31 in the front plate 32 of the casing 10, as seen in Fig. 3.

In this way the speed of movement of the vehicles in connection with which my improvements are utilized, may be ascertained at all times.

At a point diametrically opposite to its extension 19a, the actuating ring 19 has a second slotted extension 19b through which the laterally projecting pin 30 at the inner end of a lever 34, projects. This lever is fulcrumed at 35 upon a bracket 36 secured to and insulated from the casing 10, and downward movement of the outer end of lever 34, which I term a contact lever, is normally resisted by a spring 37 connected at its lower end thereto, and at its upper end to the bracket 36.

Extending horizontally within the lower

portion of the casing 10, is a contact arm 38 having one end disposed beneath the outer end of the contact lever 34 and normally in spaced relation thereto, and having 5 its opposite end pivoted to a portion of the casing at 39 and insulated therefrom. This contact arm 38 is held by a spring 40 against the insulated cam 41 of a shaft 42 mounted below the arm 38 and having a key slot 43 10 extending longitudinally therein from its outer end.

The shaft 42 is also provided with a gear segment 44 in engagement with the gear 45 of a stud shaft carrying a vertically disposed number wheel 46 whose surface is adapted to show through a sight opening 47 15 of the front 32 of the casing adjacent an opening through which access may be had to the shaft 42.

20 To the pivoted end of the contact arm 38 is extended a wire 48 leading, for instance, from the magneto of a vehicle driven by an internal combustion engine or, from the battery circuit of an electrically driven vehicle, 25 so that when the speed of the vehicle increases to a point where vertical movement of the actuating ring serves to shift the contact lever 34 into engagement with the contact arm 38, the circuit will be grounded 30 through the contact lever 34 and shafts 11 and 14.

It is obvious that by thus grounding the 35 circuit the speed of the vehicle may be controlled so as not to exceed a given point, determined by the normal relative position of the lever 34 and arm 38, to adjust which the operator inserts a key (not shown) within the key slot 43 of shaft 42 and by rotating 40 said shaft, shifts the contact arm 38 either toward or away from the lever 34, dependent upon whether it is desired to permit an increase, or secure decrease, of speed at the point of control.

Thus, inasmuch as the number wheel 46 45 is geared to the shaft 42, it will indicate at all times that rate of speed beyond which the vehicle cannot proceed, so that by setting the wheel 46 to the zero point, it is obvious that the lever 34 and arm 38 will be in contact 50 with one another as seen in Fig. 1, and the vehicle will then be locked against movement.

It is obvious that if so desired, a suitable

trip indicator or odometer may be utilized within the casing 10 in addition to the parts 55 above described, to be actuated by worm gears seen at 49 in Fig. 1, the indicating wheels of which may show through a slotted opening 50 in the casing's front plate 32.

Thus, from the foregoing description it 60 will be obvious that my invention provides a simple effective speedometer in its complete form, which will show the correct speed of a vehicle in connection with which it is utilized, at all times, and that as proposed, the device will not only operate to lock the vehicle against movement, but may be adjusted to control the speed of the vehicle and set a desired point in the speed, beyond which the vehicle cannot proceed. 70

I claim:

1. A speed measuring and controlling device comprising a casing, a rotatable shaft within the casing, a member slideable with respect thereto, a centrifugal device controlled by the rotation of the shaft, for shifting said sliding member with respect thereto, a pair of actuating levers having connection with said sliding member at relatively opposite sides, a speed indicating 80 wheel, connections between one of said levers and the said wheel for actuating the latter in proportion to the shifting movements of said slideable member, a contact arm within the casing adjacent to the other of said 85 levers, means including a rotatable member for adjusting the said contact arm toward and away from its respective lever, and an indicating wheel having a geared connection with said rotatable adjusting member, for 90 the purpose described.

2. A speed measuring and controlling device comprising a casing, a rotatable shaft therein, a centrifugal device mounted on and controlled by the rotation of said shaft and including a member slideable on the shaft, an actuating ring carried by said slideable member, a speed indicating device having connection with said ring, a lever within the casing also having connection with the ring, a contact arm engageable by said lever, means for adjusting said contact arm toward and away from the lever, and means for indicating the degree of adjustment thereof, all for the purpose described. 100

JAMES HENRY CORE.
